W. ANTHONY,
ELECTRICAL MEASURING INSTRUMENT,
APPLICATION FILED SEPT. 5, 1916.

1,273,126.

Patented July 23, 1918.

INVENTOR

William Anthony,
By Bern. Bernor Crampton,
His attorney.

UNITED STATES PATENT OFFICE.

WILLIAM ANTHONY, OF CLYDE, OHIO.

ELECTRICAL MEASURING INSTRUMENT.

1,273,126.

Specification of Letters Patent. Patented July 23, 1918.

Application filed September 5, 1916. Serial No. 118,497.

To all whom it may concern:

Be it known that I, WILLIAM ANTHONY, a citizen of the United States, and a resident of Clyde, in the county of Sandusky and 5 State of Ohio, have invented a certain new and useful Electrical Measuring Instrument; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates to electrical measuring instruments, and more particularly to ammeters of the pocket type.

An object of my invention is to simplify 20 and cheapen the construction of instruments of the character described by making a body-frame and the coil and needle-holding spool in two separate pieces, whereby the body-frame can be made of a cheaper material than the spool, and by providing simple 25 and efficient means for easily and quickly securing the frame and spool together in a rigid, strong and durable manner.

A further object of my invention is the provision, on the coil-carrying spool, of improved 30 needle pivot bearing means, which is capable of easy, quick and accurate adjustment to facilitate the instrument assembling.

The invention is fully described in the following specification, and while, in its 35 broader aspect, it is capable of embodiment in numerous forms, a preferred embodiment thereof is illustrated in the accompanying drawings, in which—

Figure 1 is a face view of an instrument 40 embodying my invention. Fig. 2 is a face view of the invention, with the case removed. Figs. 3 and 4 are side and rear views thereof, respectively. Fig. 5 is a perspective view of the body-frame and coil spool in 45 separated relation, and Fig. 6 is a different perspective view of the coil spool from that shown in Fig. 5.

Referring to the drawings, 1 designates 50 the body-frame of the instrument, which frame comprises a single piece stamped preferably from sheet steel and having its outer end of segmental form to conform to the circular side wall of the case 2 in which it is mounted. The side edges of the frame, 55 in the present instance, are inwardly inclined in converging relation and each has

an integral leg 3 projecting transversely therefrom to rest against the front wall of the case 2 and space the frame therefrom. A pair of integral tongues 4 project forward from the inner end of the frame 1 in transversely spaced relation with respect to the frame and each is provided at its outer end with a longitudinally projecting spur 5 preferably disposed adjacent to its inner 60 edge. An integral tongue 6 is struck rearward from the central portion of the frame 1 and carries the magnet 7 at the rear of the frame in spaced relation thereto and with its poles projecting beyond the inner 65 edge of the frame, as shown.

A scale 8, over which the indicator needle travels, is mounted on the front side of the frame 1 and is viewed exteriorly of the case 2 through a window 9 in the front thereof, 75 as is customary with instruments of this character.

The spool 10, on which the coil 11 is wound, is stamped or otherwise suitably formed in a single piece from sheet metal, 80 preferably brass, and has the opposed legs 12, 12 and the cross-piece 13 connecting the inner ends of said legs. The legs 12, 12 are suitably spaced to adapt them to fit closely 85 between the tongues 4, 4 of the frame 1 and are provided at their outer or free ends with outwardly projecting fingers 14, which are intended to bear flat against the inner sides 90 of the tongues 4 to prevent an outward longitudinal separation of the frame and spool. The spool legs are rigidly secured in this position to the tongues 4 by bending the spurs 5 inward over the fingers 14 and at the outer sides thereof to firmly hold such 95 fingers to the tongues, as shown in Fig. 3. It is evident that this provides a simple and efficient means for securing the frame and spool in assembled relation. When the spurs 5 have been bent over into holding engagement with the fingers 14, the tongues 4 then form legs which coöperate with the legs 3, 3 to support the frame 1 in spaced relation to the front of the case 2.

Each leg 12 of the spool is preferably 105 broadened at each side edge thereof between its inner end and the finger 14, and these broadened portions are rounded inward so that the body portion of the leg on which the coil is mounted is of segmental form in cross-section to facilitate a winding of the 110 coil thereon.

The cross-piece 13 of the spool is prefer-

ably broader than the legs 12 to project transversely in both directions therefrom, and one edge of the cross-piece, the front, in the present instance, is provided with an integral lug 15 projecting outward transversely therefrom and having a slight depression 16 in its inner side to form the bearing for one end of the needle-pivot 17. The opposite side edge of the cross-piece 13, or that disposed, in the present instance, adjacent to the front of the case, is provided with a U-shaped extension 18, the legs of which project forward and outward from the respective end portions of the cross-piece 15 transversely thereof so that the looped portion of the extension 18 is disposed over the bearing lug 15 in spaced relation thereto and in position to form a pivot end bearing in opposition to said bearing lug. For this purpose the inner side of the looped portion of the extension 18 is provided centrally thereof with a punch-mark 19 in axial relation to the punch-mark in the bearing lug 15, and for receiving the respective end of 25 the needle-pivot 17. The space between the bearing lug 15 and the loop or bearing portion of the extension 18 when turned outward in bearing position is greater than the length of the needle-pivot 17 to permit the placing of said pivot in proper position between said parts. This having been done, the looped portion of the extension 18 is forced inward for a portion of the length thereof between the legs of said extension 30 so as to place the pivot bearing portion of such extension in proper bearing relation to the respective pivot end. The inward forcing of the central looped portion of the extension 19 in this manner causes a stretching or drawing out of the metal composing 35 the same so that the bearing portion of such extension will remain permanently set in any position to which it may be drawn. This is found in practice to provide an exceedingly simple means for assembling the indicator needles and spools and is, so far as I am aware, a considerable improvement over the method heretofore employed of mounting needle-pivots in the frames of instruments of this character. A suitable tool 40 is provided for drawing the bearing loop 18 inward and enables a very accurate and close adjustment of the pivot bearings to be obtained in an easy and rapid manner.

55 The cross-piece 13 is provided with an opening 20 through which the indicator needle 21 projects into position to register with the scale 8. The armature 22, that is carried by the pivot 17 at one side of the 50 needle 21, also has a turning movement into the opening 20.

The conductive coil 11, which is mounted on the spool 10, has one end connected to a leg 3 of the frame 1 and in electrical connection through said frame with a post 23,

which projects from a lug 24 at the outer end of the frame 1 through the side wall of the case 2 and carries a nut 25 for binding a lead 26 thereto, as is customary in instruments of this class. The other end of the 75 coil 11 has connection, not shown, with a contact post 27, which is insulatingly carried by the case 2 in opposition to the post 23. It will, of course, be understood that the passage of a current through the coil 11 will act on the armature 22, and, if the current is sufficient, will influence a movement of said armature against the magnetic influence of the magnet 7 thereon.

I wish it understood that my invention is 80 not limited to any specific construction, arrangement or form of the parts, as it is capable of numerous modifications without departing from the spirit of the claims.

Having thus described my invention, what 85 I claim as new, and desire to secure by Letters Patent, is—

1. In an instrument of the class described, a magnet-carrying frame, and a coil-carrying spool, said frame and spool having interengaging tongues for rigidly securing the 90 two together.

2. In an instrument of the class described, a magnet-carrying frame, a coil-carrying spool of U-form, said frame and spool having interengaging tongues for rigidly securing the 95 two together.

3. In an instrument of the class described, a magnet carrying frame, a coil and indicator needle carrying frame of U form, and 100 means for securing the leg terminals of said latter frame to an edge of the magnet carrying frame.

4. In an instrument of the class described, a magnet-carrying frame, and a member 105 forming a coil-carrying spool and an indicator-needle carrying part, said frame and member having interengaging tongues for rigidly securing the two together.

5. In an instrument of the class described, 110 a magnet-carrying frame having spaced laterally projecting tongues at its inner end and a coil-carrying spool of U-form having its legs adapted to fit between said tongues and outwardly bent at their ends to engage 115 the inner sides of respective tongues, said tongues having parts bent around the bent end portions of the legs to firmly hold the same.

6. In an instrument of the class described, 120 a magnet-carrying frame and a coil carrying spool, the latter of U-form, both having tongues transversely projecting from their inner ends and interengaging to firmly unite the two.

7. In an instrument of the class described, 125 a coil carrying spool having a cross-piece at its outer end and needle-pivot bearings projecting outward from said cross-piece and one comprising a strip which is connected at 130

- its ends to longitudinally spaced portions of said cross-piece and capable of stretching when drawn intermediate its ends toward the other bearing.
- 5 8. In an instrument of the class described, a coil carrying spool of U-form having integral upper and lower needle-pivot bearings on its crown portion, with one of said bearings forming a strip extending lengthwise 10 of the crown and connected at its ends thereto, said strip being capable of stretching and remaining permanently set when drawn intermediate its ends toward the other bearing.
- 15 9. In an instrument of the class described, a coil carrying spool having spaced legs on which a coil is wound and having a cross-piece connecting said legs at one end, said cross-piece having a bearing projecting outward 20 from one side edge thereof and having a U-shaped bearing strip projecting outward from its opposite edge, with its legs connected to said cross-piece, said strip being adjustable to vary the space between it and said bearing and to coöperate therewith to 25 carry a needle-pivot.
10. In an instrument of the class described, a coil carrying spool having spaced integral needle-pivot bearings at its outer end, with one bearing connected at both ends 30 to said spool and capable of adjustment intermediate its ends toward and away from the other bearing.
11. In an instrument of the class described, a magnet carrying frame, a coil and 35 indicator needle carrying frame, and means operable to engage said latter frame to the edge of the magnet carrying frame.
- In testimony whereof, I have hereunto signed my name to this specification.

WILLIAM ANTHONY.
